Primary Examiner — John Windmuller*Assistant Examiner* — Steven J Czyz(74) *Attorney, Agent, or Firm* — Keisling & Pieper PLC; David B. Pieper(57) **CLAIM**

The ornamental design of a bow template, as shown and described.

DESCRIPTION

FIG. 1 is a perspective view of a bow template, shown with environment;

FIG. 2 is a front view thereof, shown with alternative environment;

FIG. 3 is a left side view thereof;

FIG. 4 is a right side view thereof;

FIG. 5 is a top view thereof; and,

FIG. 6 is a bottom view thereof.

The broken lines depict environment that forms no part of the claimed design.

1 Claim, 3 Drawing Sheets(56)
